HEAD RAISING AND LOWERING ATTACHMENT FOR DRILL PRESSES

James H. Dodson, Mobile, Ala.

Application April 7, 1952, Serial No. 280,881

3 Claims. (Cl. 77—28)

1 The present invention relates to drill presses, and more especially to those of the type having a hollow upright column on the upper end of which a head carrying the drill spindle is mounted.

In presses of this type, the head is normally locked to the column during operation, but in order to adjust the press to accommodate a wider range of work, it becomes necessary to raise or lower the head on the column. Such adjustments are difficult to make and are dangerous to the operator because the head is heavy, especially when, as usual, it carries an electric motor for driving the drill spindle.

The primary object of the present invention is to provide an attachment which is of relatively simple and inexpensive construction and may readily be applied to drill presses of the type referred to without requiring any modification of the press, and which enables the drill press head to be raised or lowered easily and with safety to the operator, the attachment when applied avoiding interference with either the work to be operated upon by the press or with the usual operation of the press.

Another object of the invention is to provide such an attachment which is connected to the press head in alignment with the column and centrally of the weight of the head, so that the force applied by the attachment to raise or lower the head will be in alignment with the column, and the head will therefore glide smoothly and with minimum friction on the column.

The preferred embodiment of the invention is shown in the accompanying drawing wherein—

Figure 1 is a side elevation of a drill press of a conventional type provided with the head raising and lowering attachment according to the present invention.

Figure 2 is a vertical section on an enlarged scale, taken on the line 2—2 in Fig. 1.

Figure 3 is a detail sectional view of a locking device for clamping the head in different adjusted positions on the column.

Similar parts are designated by the same reference numerals in the different views.

In the present instance the invention is shown applied to a conventional type of bench press comprising a base 1 adapted to be mounted on a bench or table 2, a tubular upright column 3 of cylindrical cross-section having its lower end fixed rigidly in the rear portion of the base, and a head 4 which is fitted as usual to slide upwardly or downwardly on the upper end of the column, the head carrying the usual vertical drill spindle 5 provided usually with a drill chuck 6 and with

levers 7 for rotating a shaft 8 connected as usual to the drill spindle for feeding the drill to the work, which may be supported on a table 9 which is usually mounted on the column for vertical adjustment and secured thereon by a locking device 10. The portion of the head in which the drill spindle is mounted, as usual in presses of this type, extends forwardly from the column 3, and a portion of the head extends rearwardly from the column and has an electric motor 11 fixed thereon for driving the drill spindle through a belt pulley 12 and a belt 13 which cooperates with a similar pulley connected to the drill spindle in the usual manner, the motor at the rear of the head counterbalancing the forward portion of the head which carries the drill spindle.

Heretofore, the head has been locked at the desired height on the column, usually by a locking device 14 which may comprise a pair of clamping members 14a which grip the column under the action of a screw 14b, and when an adjustment was to be made, the head was unlocked, which released the support for the head and motor, and as these parts are heavy, such an adjustment could be made only with difficulty and with danger of dropping down of the head and motor and consequent liability of injury to the operator or damage to the press.

These difficulties and objections are avoided by the present invention, which may be applied readily as an attachment to existing drill presses. It comprises a sling which suspends the head in alignment with the column and substantially centrally of the weight of the head and motor, and means cooperative with the sling for raising and lowering the head by a force applied in alignment with the column. Preferably as is shown in the present instance, the sling comprises a yoke 15 composed of a strip of relatively rigid metal having legs 16 which are secured respectively to the opposite sides of the head substantially at the center of weight of the head and motor by bolts 17 threaded into the sides of the head at diametrically opposite sides of the column, the yoke extending upwardly and transversely across the top of the column. A screw 18 extends upwardly from the column and is suitably fixed non-rotatably at its upper end to the top of the yoke in alignment with the axis of the column, as by heading over the upper end of the screw as shown at 19. The screw 18 extends through and cooperates with a nut 20 which is fixed non-rotatably in the upper end of a tube 21 which is smaller than and mounted concentrically within the tubular column, the nut 20 being rotatable with this tube.

55

The lower end of the tube 21 is provided with a suitable thrust bearing, such as a flange 22 on its lower end, which rests rotatably on a plate 23 which is secured, as by screws 24, to the lower side of the bench or table on which the press rests, the plate 23 supporting through the tube 21 and yoke 15 the weight of the press head and motor. Suitable means, such as a bevel gear 25 pinned or otherwise fixed to the lower end of the tube 21 and a cooperating bevel gear 26 fixed to a shaft 27 mounted rotatably in bearings 28 on the underside of the plate 23 and provided with a crank 29, provide means for rotating the tube 21 and nut 20 and thereby raising or lowering the screw 19 and the yoke 15 and the head supported thereby.

In operation, when it is desired to raise or lower the head 4, it is only necessary to loosen the locking device 14 and thereby release the head so that the head is then supported by the screw and nut and the yoke connected thereto, and to then rotate the crank 29 in the appropriate direction to raise or lower the head as desired. Rotation of the crank operates through the bevel gears to rotate the tube 21 and nut 20, and operating to raise or lower the screw 18 and yoke 15 and the head suspended therefrom, the screw and nut supporting the weight of the head and motor during the adjustment. After the desired adjustment has been made, the head may be locked in operative position on the column by tightening the locking device 14. The co-axial relation between the screw and nut device and sling and the column also enables the head while supported thereby to be swung aside about the column as an axis without obstruction, if such is desired.

As the sling or yoke is attached to the head at the sides thereof at diametrically opposite sides of the column and at substantially the center of weight of the head and motor, and the screw and nut are located co-axially with the column, the force applied by the screw and nut to the head in raising or lowering it will be applied in alinement with the column, in consequence of which binding or undue friction of the head on the column is avoided.

The screw and nut device are housed within the tubular column where it will not obstruct or otherwise interfere with the work to be operated upon by the press, and the sling or yoke extends upwardly above the column where it will avoid obstructing the operator in operating the press.

The attachment is simple and inexpensive in construction, and it may readily be applied to existing drill presses by merely drilling and tapping two holes in the head and placing the at-

taching screws in place, and inserting the screw and nut device in the lower end of the column and attaching the mounting plate to the underside of the bench or table on which the press is mounted.

I claim as my invention:

1. An attachment for a drill press of the type having a hollow upright column and a head adjustable vertically thereon and carrying a drill spindle, comprising a yoke-shaped sling having a pair of laterally spaced arms provided with means for connecting them to opposite sides of the head and having a central portion to extend over the top of the column, and means mounted concentrically within the column and connected to the central portion of the sling for raising or lowering the head.

2. In a drill press of the type comprising a tubular column and a head mounted for raising and lowering movement thereon and carrying a drill spindle at one side of the column and a counterbalancing drill spindle operating motor at the opposite side of the column, a sling having a central portion extending transversely over the top of the column and having legs extending downwardly from its central portion and attached to the respective sides of the head at substantially the center of weight of the head and motor and at opposite sides of the column, and means mounted concentrically within the column and connected to the central portion of the sling for raising or lowering it.

3. In a drill press of the type comprising a tubular column and a head mounted for raising and lowering movement thereon and carrying a drill spindle at one side of the column, a sling having an upper central portion extending transversely across the top of the column and legs extending downwardly and laterally from its upper central portion and attached to the respective sides of the head at opposite sides of the column, a screw connected at its upper end to the upper central portion of the sling and extending downwardly into the column, a tubular member mounted rotatably within the column and concentrically thereof to receive the lower end of the screw, a nut fixed to the tubular member and cooperating with the screw, and means connected to the lower end of the tubular member for rotating it and the nut.

JAMES H. DODSON.
